PERCY S. TURNER, OF CHORLTON-CUM-HARDY, ENGLAND, ASSIGNOR TO WESTINGHOUSE ELECTRIC AND MANUFACTURING COMPANY, A CORPORATION OF PENNSYLVANIA.

SWITCHING DEVICE.

1,181,267.

Specification of Letters Patent.

Patented May 2, 1916.

Application filed May 1, 1913. Serial No. 784,972.

To all whom it may concern:

Be it known that I, Percy S. TURNER, a subject of the King of Great Britain, and a resident of Chorlton-cum-Hardy, in the 5 county of Lancaster, England, have invented a new and useful Improvement in Switching Devices, of which the following is a specification.

My invention relates to switches for use 10 in multiple-unit control systems, and it has for its object to provide improved switches and devices for supporting the same, whereby an inexpensive, compact, rugged and extremely well insulated switch group is obtained.

In multiple-unit control systems, as now generally employed, a plurality of separate and independently operated switches, commonly known as contactors or unit switches, 20 are utilized, the operation of the switches being controlled by a master controller in conjunction with interlocking switches operated by the movement of the contactors or unit switches. In apparatus of this 25 character which is designed for practically continuous service under severe operating conditions, it is very necessary that the insulating material used should be of the highest class and adapted to withstand hard 30 wear and the shocks and jolts incidental to the movement of the electric vehicles at comparatively high speeds. The insulating material which fulfils all the desired conditions is mica or some material manufactured 35 from mica or a substitute having similar properties, and it is a feature of the present invention that the supports for the switches, together with as many parts thereof as possible, are made of steel or iron insulated 40 with mica or micanite.

According to my invention, the switches or contactors are each supported on a pair of parallel rods of iron or steel inclosed in an insulating tube of mica, micanite or other 45 similar material. The rods for all the switches are arranged parallel and preferably in a horizontal plane. Such an arrangement renders the length of the entire group of switches much smaller than it 50 would be if the switches were arranged end to end upon a single pair of parallel supports, since a certain distance, commonly called the creeping distance, must, in the latter case, be allowed between the several

switches, which lengthens the entire apparatus.

A further advantage of my invention is that the insulating material of each switch is independent of that of the other switches so that, if the insulating material of one switch becomes faulty, a repair may be readily effected without disturbing any of the other switches.

The switches or contactors, which may be operated either electromagnetically or by means of compressed air electromagnetically controlled, as in the present well-known systems, may be of any suitable description.

In order that the nature of the invention may be clearly understood, it will now be described with reference to the accompanying drawing in which—

Figure 1 is a view in front elevation and Fig. 2 a plan view showing means for supporting contactor switches according to my present invention. Fig. 3 is a section on line III—III of Fig. 1.

A plurality of parallel carriers 1, here shown as angle irons, are supported from the under frame or the floor of a car in any convenient manner (not shown). Suspended from the carriers 1 by plates 2, which are attached thereto by bolts 16, are a plurality of parallel rods or tubes 3 severally surrounded, for the greater portion of their lengths, by insulating tubes 4 of micanite or other suitable material. The rods or tubes 3 are arranged in pairs, each pair supporting one contactor switch with its interlocking switches and operating means complete (not shown); a portion of such a contactor switch being indicated in outline at 5. The support for the switch comprises a plate 6 having end portions 7 bent partially around the corresponding tube 4 and projecting above the tubes, as indicated at 8, to coöperate with clamping plates 9 which are also bent to partially surround the tubes. The upper ends of the plates 6 and 9 are clamped together by bolts 10, and the lower ends of the plates 9 are secured to the parts of the corresponding plates 6 which are below the supporting rods 3 by bolts 11. Severally attached to said lower parts of the plates 6, also by the bolts 11, are side plates 12 the lower ends of which are turned inwardly to form ledges or shelves 12^a to receive flanges 13 with which the upper por-

tion of the contactor switch 5 is provided. The upper portion of the switch 5 is also provided with flanges 14 at the front and rear which are attached to the plate 6 by means of bolts 15. The flanges 13 are made of such dimensions that the switches to which they belong may be readily moved into, or out of, position when the bolts 15 are removed, and, if the distances between the 10 clamping devices of the switch supports are not uniform, the necessary adjustment of the rods or tubes 3 toward, or away from, each other may be effected by turning the plates 2 upon the bolts 16 the necessary 15 amount.

It will be seen that, by the system above described, each switch is independently supported and may readily be removed for inspection and repair without necessitating 20 the removal of adjacent switches; also, if any failure of the insulating material occurs between a supporting rod or tube 3 and the clamps 7, 9, 10 and 11 by means of which the switch is suspended, the faulty 25 rod may be readily removed without necessitating the dismounting of other switches. Furthermore, the structure is rendered very compact because the creeping distance between one switch and the 30 next depends on the distance between the clamping and supporting devices, and is independent of the actual distance between adjacent switches. Suitable insulating material or other material for shields may be 35 attached, if desired, between the adjacent switches to form cells, each one of which contains a switch.

I claim as my invention:

1. The combination with a plurality of 40 switches and main carrying means therefor, of a plurality of pairs of rods severally disposed perpendicularly to said carrying means, and a plurality of sets of detachable hangers for severally engaging said pairs 45 of rods and supporting said switches.

2. The combination with a plurality of switches and main carrying beams therefor, of a plurality of separate pairs of independent parallel rods severally attached 50 perpendicularly to said beams, and an equal plurality of sets of hangers for severally detachably encircling the rods in the several pairs and severally supporting said switches intermediate each of said pairs, 55 said sets severally comprising a plurality of independent plates of substantially U-shape attached to said switches, and a plurality of independent curved clamping bars detachably associated with each end of said 60 plates for respectively engaging one of said rods and one of said switches.

3. In a switch-supporting device, the combination with a plurality of independent pairs of supporting rods, of an equal plurality of sets of hangers for severally 65 detachably encircling the rods in the several pairs and severally supporting said switches intermediate each of said pairs, said sets severally comprising a plurality of independent plates of substantially 70 U-shape attached to said switches, and a plurality of independent curved clamping bars detachably associated with each end of said plates for respectively engaging one 75 of said rods and one of said switches. 75

4. In a switch group, the combination with a plurality of switches and carrying means therefor, of a plurality of pairs of insulated rods severally disposed perpendicularly to said carrying means, and a plurality of sets of detachable hangers for severally engaging said pairs of rods and supporting said switches. 80

5. In a switch group, the combination with a plurality of switches and carrying means therefor, of a plurality of insulated rods severally disposed perpendicularly to said carrying means, means for adjustably supporting said rods, and detachable hangers for suspending said switches from said 90 rods. 85

6. In a switch-supporting device, the combination with a plurality of pairs of insulated rods, of a plurality of pairs of detachable hangers supported by said pairs of rods and having recesses to receive and support said switches. 95

7. In a switch-supporting device, the combination with a plurality of pairs of rods, of adjustable means for supporting 100 said rods at any selected distance from each other, pairs of detachable hangers for engaging said pairs of rods and having recesses for receiving and detachably supporting said switches. 105

8. In a switch-supporting device, the combination with a plurality of pairs of rods, of adjustable means for supporting said rods at any selected distance from each other, a plurality of pairs of detachable 110 hangers for engaging said pairs of rods and having recesses for receiving and detachably supporting said switches, and means for clamping said switches to said hangers. 115

In testimony whereof, I have hereunto subscribed my name this eleventh day of April 1913.

PERCY S. TURNER.
